UNITED STATES PATENT OFFICE

RICHARD E. BISSELL, OF CLEVELAND HEIGHTS, OHIO, ASSIGNOR TO THOMPSON PRODUCTS, INC., A CORPORATION OF OHIO

VALVE FOR INTERNAL-COMBUSTION ENGINES

Application filed April 20, 1927. Serial No. 185,099.

This invention relates to valves for internal combustion engines and more particularly to exhaust valves.

Such exhaust valves are subject to a high degree of heat from the hot products of combustion. This heat is dissipated largely by conduction along the valve stem and from thence by conduction to the guide for the valve stem and by radiation and conduction into the air around the stem.

The principal object, therefore, of the present invention is to provide means for increasing the rate of flow of heat from the hot portions of the valve to cool portions, especially in hollow stem valves.

According to my invention, therefore, a member of relatively high heat conductivity is arranged within the valve stem to aid in the conduction of heat from the head to the tail of the valve.

As this member may be wholly enclosed within the stem the metal or alloy for making the same may be selected without regard to corrodibility. Further, as the walls of the stem carry the strains and stresses, the strength or hardness of such metal or alloy is likewise immaterial.

The chief requirement is a high heat conductivity. A secondary advantageous requirement is that the co-efficient of expansion by heat shall be as nearly the same as that of the metal forming the valve head and stem as possible.

On the basis of heat conductivity, copper is one of the best materials for my purpose. Aluminum and magnesium also have high heat conductivities much greater than that of steel although less than that of copper. Where extreme lightness is concerned, aluminum or magnesium may be preferable to copper since, for equal weights of metal, both aluminum and magnesium will conduct considerably more heat than copper.

Similarly, alloys of copper, aluminum, magnesium or other metals may be used for this purpose. Preferably the metal alloy should be one which will not fuse at any temperature attained by any part of the valve.

The variations in coefficient of thermal expansion between different metals and alloys

should be taken into consideration. The coefficient of heat expansion for copper is nearer that of steel than either aluminum or magnesium. Hence from the point of view of thermal expansion, copper again is to be preferred as it expands and contracts with heat much more nearly in accordance with steel than either of the other metals mentioned.

Provision should be made for variations in thermal expansion of the steel stem of the valve and the copper or other member within the stem. This may be brought about in various ways such as providing adequate play laterally and longitudinally between such member and the interior of the valve stem or else the member is connected at its ends only, and the member is bent intermediate its length to provide for longitudinal expansion.

Other objects and features of the invention will be hereinafter set forth in connection with the accompanying drawings which set forth the invention in its preferred form.

On the drawings:

Figure 1 is a longitudinal, central section through a valve constructed in accordance with the present invention.

Figure 2 is a detail sectional view on an enlarged scale of the lower end of the valve stem.

Figure 3 is a section on the line III—III of Figure 1.

Figure 4 is a longitudinal central section through a further modification.

Figure 5 is a detail sectional view on an enlarged scale of a still further modified form of construction.

Figure 6 is a detail sectional view on an enlarged scale of yet another form of construction.

The form of construction shown in Figures 1, 2 and 3 comprises a head 1 and a hollow stem 2 integrally formed therewith. Within the bore of the stem is a copper rod 3. With the parts proportioned as shown, making the stem hollow and inserting a copper rod therein will increase the heat conductivity of the central part of the stem while decreasing the weight of the same part as compared with a solid steel stem. The bore 4 of the stem is made with restricted portions

5 and 6 at the ends adapted to support the ends of the copper rod 4. Enough play is provided between the restricted portions 5 and 6 of the bore and the copper rod so that under the maximum temperature attained, the expansion of the copper with respect to the steel will not do more than close the space around the ends of the rod and thus avoid the production of any bursting or disruptive strains in the valve head or stem. The space left for expansion should be greater at the head end than at the tail end of the valve.

The space between the main part of the rod and the valve stem is greater than that required to allow for relative thermal expansion in order to reduce weight and also to cause the heat to flow directly from the hottest part of the valve, its head, to the coolest part, its foot, without appreciable influence from the intermediate parts of the valve stem. With such an arrangement, a greater equalization of heat is obtained than would be possible otherwise, thereby restricting the liability to warpage and the like.

In making this form of construction the lower end of the valve is bored out to the maximum diameter of the stem bore and threaded internally. Next the copper tube 7 is inserted and finally a steel sleeve or plug is screwed into the valve stem to produce the restricted part 9. This sleeve is bored to receive the lower end of the copper rod 3 and threaded for the reception of the screw plug 10.

After the rod 3 has been inserted, a screw plug 10 is inserted to close the interior of the valve. The usual hardened steel tip 15 is then inserted when the valve is ready for use.

Longitudinal differential expansion is provided for in forms shown in Figures 1 to 3 inclusive by making the length of the bore of the stem somewhat greater than the length of the rod 3.

In the construction shown in Figure 4, a different method of allowing for longitudinal differential expansion is shown. In this case, the copper rod 11 is brazed to the upper or head end of the bore of the stem at 12. The lower or tail end of the rod 11 is passed through a plug 13 adapted to fit the lower end of the bore of the stem. After the rod 11 and plug 13 have been inserted, these parts are brazed at 14 to the tail end of the stem. The usual hardened steel tip 15 is then inserted.

In Figures 5 and 6, alternative means for securing the lower end of the copper rod are illustrated. The construction shown in Figure 5 is produced by forging a solid valve and stem with an enlarged lower end, then boring out the stem and finally closing the lower end of the stem and simultaneously gripping the lower end of rod 16 by swaging.

The exterior of the valve is then turned to the desired form and size.

In Figure 6, a threaded plug 17 is employed to which the lower end of the rod 18 is brazed at 19.

I am aware that many changes may be made, and numerous details of construction may be varied through a wide range without departing from the principles of this invention, and I therefore do not purpose limiting the patent granted hereon, otherwise than necessitated by the prior art.

I claim as my invention:

1. A valve for internal combustion engines comprising a head, a stem, and a member wholly enclosed within the stem of material having a greater heat conductivity than the stem.

2. A valve for internal combustion engines as in claim 1 in which the member consists chiefly of copper.

3. A valve for internal combustion engines comprising a head and a hollow stem, and a rod wholly enclosed within said stem having heat transferring contact at one end with the valve head and at the other end with the tail of the valve stem, said rod being formed of material having a greater heat conductivity than the stem.

4. A valve for internal combustion engines comprising a head, a hollow stem and a member wholly enclosed within the stem of material having greater heat conductivity than the stem, the parts being so proportioned that the heat conductivity of the stem and member is greater and the combined weight is less than that of the stem if solid.

5. A valve for internal combustion engines comprising a head and hollow stem and a member of higher heat conductivity than said stem arranged within said stem adapted to contact with said stem adjacent its ends only thereby transferring heat directly from the valve head to the foot of the stem.

6. A valve for internal combustion engines comprising a head and hollow stem and a member of higher heat conductivity than said stem arranged within said stem adapted to contact loosely with said stem adjacent its ends only thereby transferring heat directly from the valve head to the foot of the stem.

In testimony whereof I have hereunto subscribed my name at Cleveland, Cuyahoga County, Ohio.

RICHARD E. BISSELL.
